CHARLES H. REICHMANN, OF NEW YORK, N. Y.

Letters Patent No. 60,937, dated January 1, 1867.

IMPROVEMENT IN LAMP CHIMNEYS.

The Schedule referred to in these Letters Patent and making part of the same.

TO ALL WHOM IT MAY CONCERN:

Be it known that I, CHARLES H. REICHMANN, of the city, county, and State of New York, have invented a new and improved Glass Chimney for Lamps; and I do hereby declare that the following is a full, clear, and exact description thereof, which will enable those skilled in the art to make and use the same.

The drawing represents a sectional elevation of my invention.

The object of this invention is to obtain a glass draught chimney for lamps, which will not be liable to break or fracture under expansion due to the heat of the flame. Glass chimneys, as at present constructed, break or fracture under unequal expansion, the upper part of the chimney, being heated much more intensely than the lower part, expands in a proportionately greater degree, and fracture is the result. I design to obviate this difficulty by constructing the chimney in two sections, connected together in such a manner as to form secure and close joints, and which will admit of said sections or parts expanding separately or independently of each other, as hereinafter fully shown and described.

In the present example the chimney is shown constructed of two parts, A, B, both of glass. The lower part, A, corresponds in form to the lower parts of the ordinary glass chimneys in use, and may be secured upon the burner in any of the known ways. The upper end of this part A curves outward to form a flange, *a*, as shown clearly in the drawing. The upper part, B, of the chimney may be of cylindrical, conical, or other proper form, and has its lower end curved outward to form a flange, *b*. This flange, *b*, rests upon the flange *a* of the lower part, A, of the chimney, and said flanges are encompassed by a metallic band, C, the upper part of which is bent over flange *b* of B, and the lower part indented externally to form projecting spurs, *c*, at its inner side to fit under the flange *a*, of the part A, and secure the two parts A, B, together. This band need not be wider than just enough to clasp both flanges, and is too narrow to offer any serious obstruction to the light. It is not designed to have the metallic band, C, fit tightly around the parts A, B, but loosely, so that either part may expand freely and independently of each other and the band C. Hence it will be seen that the upper part, B, which is heated in a much greater degree than the lower part, A, may expand proportionably more, without at all affecting A, while the comparatively slight expansion of A will not affect the part B. The breaking or fracturing of glass lamp chimneys from the cause above stated, renders the burning of coal oil and other similar hydro-carbons rather expensive and very annoying. Many plans have been devised to obviate the difficulty. Mica chimneys have been used, but they have proved a failure, as they soon become discolored by the lodgment of unconsumed carbon between the laminæ, and will not bear the friction of a cloth or cleaner; besides, it is very difficult to obtain mica in sufficiently large sheets and of good quality. Chimneys have also been constructed with sheet-metal tops and glass lower parts. These, so far as breakage from unequal expansion is concerned, have proved to be a success, but they have not come into general use on account of obstructing the light. They will answer for lamps to read or sew by, but do not give that cheerful light which is required for the general illumination of a room.

My invention, it will be seen, possesses the advantage of the combined metal and glass chimney, and at the same time will not obstruct the light as is the case with the former, not any more than the ordinary glass chimney blown or moulded in one piece.

I am aware that projections have been made on the upper side of the lower part of chimneys constructed in parts, which projections catch and slide in a groove on the inside of the metal band, necessitating a certain position of all parts to be fitted together, but in my invention the two parts A, B, may be connected and disconnected at any time, even in the dark, with the greatest ease, as no particular position of the parts is necessary to insure a complete fitting together of the same, the metal band being simply slid over the upper part until it rests on the flange of the same, and then sprung over the flange of the lower part.

In this way the chimney may be taken apart and cleaned with rags without requiring a long wiper, which often causes the breaking of the chimney.

Having thus described my invention, I claim as new, and desire to secure by Letters Patent—

A glass chimney for lamps, constructed of two sections, the adjoining parts of which are provided with flanges *a* *b*, held together by a narrow metal band, slipped over the upper part and resting on its flange, and sprung over the flange of the lower part.
